Attorneys,

UNITED STATES PATENT OFFICE.

LULU S. LEE, OF LOS ANGELES, CALIFORNIA.

DESIGN FOR A BADGE.

No. 40,116.

Specification for Design.

Patented July 6, 1909.

Application filed April 22, 1909. Serial No. 491,652. Term of patent 7 years.

To all whom it may concern:

Be it known that I, LULU S. LEE, a citizen of the United States, residing at Los Angeles, in the county of Los Angeles and State of California, have invented a new, original, and ornamental Design for Badges, of which the following is a specification, reference being had to the accompanying drawing, forming part thereof.

The figure is a face view of a badge, showing my new design.

I claim:

The ornamental design for a badge, as shown.

LULU S. LEE.
